UNITED STATES PATENT OFFICE.

WALTER KNOWLES TROTMAN, OF WOOD GREEN, LONDON, ENGLAND.

APPARATUS FOR WATERMARKING PAPER.

984,618.

Specification of Letters Patent. Patented Feb. 21, 1911.

Application filed March 24, 1908. Serial No. 422,945.

To all whom it may concern:

Be it known that I, WALTER KNOWLES TROTMAN, a subject of the King of England, residing at Wood Green, London, England, have invented certain new and useful Improvements in Apparatus for Watermarking Paper, of which the following is a specification.

This invention relates to improvements in apparatus for watermarking paper, namely, the dandy rolls (wove, laid and spiral-laid) and flat frames (wove or laid) used for that purpose. In my previous United States Patent No. 821206 I have described a dandy roll 15 the cylindrical portion of which has one or more removable sections carrying the watermarking devices and the apparatus embodying the present invention belongs to the same type. In the arrangement described in my prior patent, the cylindrical portion of the dandy roll had a space therein and a section of backing carrying a detachable or other gauze covering was arranged to fit into the space in the backing. 25 but in the present invention the backing (either of a dandy roll or flat frame) is made in the ordinary way—complete, comprising for example (in the case of a dandy roll) a shaft carrying a series of rings with 30 longitudinal wires or rods thereon having a spiral backing sheet wound on the rods and rings.

According to this invention an apparatus for watermarking paper comprises the combination with a permanent backing of a gauze covering having one or more removable sections carrying the watermarking devices. The gauze covering has spaces therein and is permanently attached to the backing and projections and recesses are provided both on the backing and on the removable gauze sections and are arranged to engage one another so as to retain the sections in position. In constructing a dandy 40 roll in accordance with this invention, the permanent backing is made up in any usual way. The wire gauze covering having spaces therein is permanently secured to the backing, the circumferential edges of the 45 covering at such spaces being soldered, fused or otherwise secured to the usual rings of the backing; and positioning devices are provided on the removable gauze sections and on the backing so that the sections can 50 be accurately placed in position in the spaces

in the covering and can be securely held therein when in use.

In the accompanying drawings:—Figures 1 to 4 illustrate one method of carrying this invention into effect on a dandy roll having a laid covering. Fig. 1 is an elevation partly broken away. Fig. 2 is a transverse section on the line 2—2 of Fig. 1; and Figs. 3 and 4 are enlarged perspective views of details. Fig. 5 is an elevation partly broken away, and Fig. 6 is a transverse section on the line 6—6 of Fig. 5, showing a method of carrying this invention into effect on a dandy roll having a wove covering.

Referring first to Figs. 1, 2, 3, and 4, the main framework of the roll is constructed as usual and consists of a central shaft A having fixed thereon circular ends plates B and a series of circular open disks C. The wire gauze covering, (in this case a laid covering) is secured to the disks in any usual way and the covering consists of longitudinal wires D secured together by fine interlaced wires E constituting the laid wires and secured 80 also to the rings C. A space is left in the wire gauze covering at the place where the removable section is to occur and the cut ends of the wires of the covering are soldered, fused, brazed, sewn or otherwise secured to the rings C of the backing. Alongside the rings C to which the cut ends are soldered, are fixed half rings C¹ to serve as supports for the removable gauze section.

The removable gauze section F having 90 the watermarking device thereon terminates at its ends in a twist or stiffening wire E¹ (constituting part of the laid wires in the complete covering, as shown in Fig. 4). Projecting from the longitudinal edges of the 95 removable section F are short stiff wires G arranged to be inserted underneath the longitudinal edges of the fixed covering. The rings C of the backing and also the half rings C¹ are provided with a series of little pins H arranged to project into the edges of the removable section so that the removable section is held in position during use. It will be seen from Fig. 3 that the removable section is prevented from moving out radially by 100 the short stiff wires G and at the same time is prevented from sliding away circumferentially by the little pins H.

In order to obtain perfect registration, double sets of pins may be used, one set en- 110

gaging the permanent gauze covering and the other set engaging the removable gauze section, the distance between the sets of pins being such that the section is held accurately in position so as virtually to form part of the covering as a whole.

The method of applying the removable section is as follows:—The short stiff wires G at one edge of the removable section are inserted underneath the longitudinal edges of the fixed covering in such a position that the little pins H engage the first longitudinal wire of the removable section F. The short stiff wires G at the opposite (or second) longitudinal edge of the removable section are also inserted underneath the corresponding edge of the fixed covering and the removable section is then gently stroked or rubbed so as to cause the longitudinal wire at the second edge to ride over the corresponding pins H and the removable section is then securely held in position.

In order to detach the removable section for the purpose of substituting a section having a different watermark, it is only necessary to raise the longitudinal wire at one edge of the section off the pins H and then to pull the short stiff wires G out of engagement with the fixed covering. To facilitate this, sliding fingers J may be provided on some of the rings C immediately under one edge of the removable section and these sliding fingers may be operated by eccentrics J¹ on a rotatable longitudinal rod J² operated from the end of the dandy roll by a rotatable knob or handle J³.

Referring to Figs. 5 and 6 which illustrate a dandy roll having a wove covering and embodying this invention, the roll comprises a hollow shaft A, end plates B and a series of circular open disks C. To the periphery of these disks is attached the cylindrical frame of the roll constructed of longitudinal rods K upon which is wound (preferably spirally) a stout wire L with spaces between the convolutions. This circumferential wire L is soldered, sewn, or otherwise secured to the longitudinal rods K. The shaft A, disks C, rods K and wire L constitute the backing of the dandy roll. Upon this backing is secured a wire gauze sheet M forming the outer surface of the roll. A section of the wire gauze covering N carrying the watermarking devices thereon is removable from the roll. In this arrangement the removable section has stiffeners consisting of little metallic plates O at its longitudinal edges. Slots P are then cut in the spiral backing sheet of wire L and also if need be slots Q may be cut in the rings C near the edges of the spaces in the covering. The stiff edges O of the movable section are inserted into these slots

P Q and secured in position there. In the arrangement illustrated in Figs. 5 and 6, the stiffening plates O have slots O¹ therein and hooks or snail cams R attached to two rotatable longitudinal rods S having rotatable knobs S¹ at the end of the roll are arranged to enter the slots O¹ so that when the removable section N is placed in position with the plates O projecting into the slots P Q, and when the longitudinal rods S are rotated so as to bring the hooks R into engagement with the slots O¹, the removable section N is firmly secured in position. To replace one removable section by another carrying a different watermark, it is only necessary to turn the hooks R out of engagement with the slots O¹, when the removable section will be free. Instead of the metal plates O stiffened edges of wire or other device may be used.

The invention has been described in its application to a dandy roll having a central shaft and disks thereon but the invention is equally applicable to a dandy roll the backing of which is constructed in any other usual manner for example to a dandy roll having a backing consisting of a perforated metal sheet or a backing consisting solely of longitudinal rods and spiral windings.

It is to be understood that the details of arrangement and construction may be varied without departing from this invention.

What I claim as my invention and desire to secure by Letters Patent is:—

1. In an apparatus for watermarking paper the combination of a complete and permanent backing, a gauze covering permanently secured to said backing and having a space therein, a removable gauze section carrying the watermarking devices and adapted to fit into said space, and projections and recesses on the backing and section to engage one another and retain the section in position.

2. In a dandy roll the combination of a complete and permanent cylindrical backing comprising a shaft and a series of circular disks thereon, a cylindrical gauze covering permanently secured to said backing and having a space therein, a removable gauze section adapted to fit into said space, and projections and recesses on the backing and section arranged to engage one another and retain the section in position.

3. In a dandy roll the combination of a shaft, a series of circular disks permanently secured thereon, longitudinal rods permanently secured to said disks, a backing sheet formed of wire wound on the rods and permanently secured thereto and having longitudinal slots therein, a wire gauze sheet permanently secured to said backing sheet and having a space therein, a removable section of gauze sheet adapted to fit in said space, stiffeners at the longitudinal edges of said

section arranged to project into the slots and means for securing the stiffeners to the backing to retain the section in position.

4. In a dandy roll the combination of a shaft A, a series of circular disks C permanently secured thereto and having slots Q in their circumference, longitudinal rods K permanently secured to said disks, a backing sheet formed of wire L wound on and 10 permanently secured to the rods K and having longitudinal slots P therein, a wire gauze sheet M permanently secured to said backing sheet and having a space therein, a removable section of gauze sheet N adapted to

fit in said space, slotted stiffeners O at the 15 longitudinal edges of said section arranged to project into the slots P Q, a longitudinal rotatable spindle S in the dandy roll and hooks R on said spindle arranged to engage the slots in the stiffeners O of the removable 20 gauze section.

In testimony whereof I have signed my name to this specification in the presence of two subscribing witnesses.

WALTER KNOWLES TROTMAN.
